UNITED STATES PATENT OFFICE.

SVANTE R. W. M. BAGER, WERNER LEHMAN, AND FREDERICK C. RUHLOFF, OF SOUTH MILWAUKEE, WISCONSIN, ASSIGNEES TO BUCYRUS COMPANY, OF SOUTH MILWAUKEE, WISCONSIN, A CORPORATION OF WISCONSIN.

EXCAVATOR FRONT-END CONSTRUCTION.

Application filed March 16, 1922. Serial No. 544,323.

To all whom it may concern:

Be it known that we, SVANTE R. W. M. BAGER, WERNER LEHMAN, and FREDERICK C. RUHLOFF, all citizens of the United States, and residents of South Milwaukee, in the county of Milwaukee and State of Wisconsin, have invented new and useful Improvements in Excavator Front-End Constructions; and we do hereby declare 10 that the following is a full, clear, and exact description thereof.

This invention relates to certain new and useful improvements in excavators and refers more particularly to a front end construction for a railway type shovel.

Considerable difficulty has been experienced in the past in providing a car front end construction having substantially beveled corners, in order to permit the dipper to swing back close to the car when digging at an angle, and at the same time have sufficient strength to support the boom structure and withstand the blows of the dipper door or hinges incidental to the operator trying to get the dipper back as far as possible to start a cut or get in back of a boulder which may have rolled down close to the front end.

Hence, this invention has for a primary object to provide a car front end of the desired shape which is so designed and constructed as to properly support the weight of the boom structure and withstand the blows from the dipper.

Another object of this invention is to provide a transom structure for binding together the car body sills which structure includes inner and outer castings, the outer castings having their outer faces at an angle with respect to the car front end to form the desired beveled corners.

It is a further object of this invention to provide a reinforced front end construction having beveled corners in which the inner I-beam sills are preferably reinforced by web stiffening plates extending to a point considerably inwardly of their outer ends.

A still further object of this invention is to provide renewable buffer blocks for the transom structure castings, which blocks protect the car body front end from damage by the swinging of the dipper too close to the car front end.

With the above and other objects in view

which will appear as the description proceeds, our invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, we have illustrated one complete example of the physical embodiment of our invention constructed according to the best mode we have so far devised for the practical application of the principles thereof, and in which:

Figure 1 is a top view of the front end of a railway type shovel constructed in accordance with our invention, the boom structure being removed and parts broken away and in section;

Figure 2 is a fragmentary view, partly in section and partly in elevation, of the front buffer end, said view being taken on the plane of line 2-2 of Figure 1;

Figure 3 is a fragmentary sectional view taken through one of the separator castings on the line 3-3 of Figure 1;

Figure 4 is an enlarged fragmentary sectional view taken through Figure 2 on the plane of the line 4-4, and

Figure 5 is a fragmentary sectional view taken through Figure 1 on the plane of line 5-5.

In railway type shovels, it is highly desirable that the front ends have its corners beveled to permit the dipper to swing back close to the car when digging at an angle, and difficulty has been experienced in so designing the car body front end and at the same time provide sufficient strength to support the boom structure and withstand the frequent blows imparted thereto by the dipper door or hinges incidental to the operator endeavoring to position the dipper back as far as possible to start a cut, or get in back of a boulder which may have rolled down close to the front end. It was formerly customary to obtain this construction by extending the inner I-beam or sills 5 beyond the outer sills or I-beams 6, the beveled corners then being formed either by bending suitable outer structural members, such as I-beams or channels, or more frequently by

riveting a bent plate extending around the corner.

This construction did not enable the outer sills 6 to reinforce the inner sills 5 and assist them in supporting the heavy weight of the boom (not shown) swivelled on a support 7 mounted on a main base plate 8 at the car body front end. Hence, the inner I-beams frequently broke, and other structures devised to provide the required strength sacrificed the advantages of the beveled corners, which is important to permit the dipper to swing back close to the car when digging at an angle. In the accompanying drawing, the advantages of the beveled corners are obtained together with the requisite strength to support the boom structure and prevent damage to the car end by the dipper.

As clearly illustrated in Figure 1, the forward ends of sills 5 extend beyond the adjacent ends of sills 6 and the inner and outer sills are bound together by a transom structure including separator castings 9, the outer ends of which are inclined forwardly and inwardly to provide the desired bevel to the car corners. Each separator casting has a rearwardly projecting tubular part 10 which is positioned between the adjacent inner and outer sills and extends preferably to a point adjacent the inner end of base plate 8, and the tubular part is reinforced by a transverse web 10'. Castings 9 are secured in position by vertical bolts 11 which pass through base plate 8 and the separator castings and transverse bolts 12 which pass through the adjacent inner and outer sills and the castings. To provide additional strength and bring the top faces of the separator castings 9 flush with the top faces of the I-beams 5 and 6 to form an unbroken surface for receiving the base plate 8, the longitudinal corners of each casting are channeled, as at 9', so that their sides each have a snug fit in the channel of the adjacent I-beam and their top faces are on a plane level with the upper faces of the I-beams.

The space between the forward ends of the inner sills is enclosed by a front buffer or bridge casting 13, the ends of which are formed with inwardly projecting flanges 14 for securement to the webs of the inner sill 5 by bolts 15. Bolts 15 also serve to anchor the forward ends of the separator castings and secure a stiffener plate 16 to the inner web face of each sill 5. The stiffener plates 16 extend rearwardly of the base plate inner end and are also secured to sills 5 by the bolts 12.

A rearwardly projecting bottom flange 17 is formed on casting 13, the ends of which overlap the separator castings and are secured thereto by bolts 18. The intermediate portion of casting 13 is braced by a depending flange or apron 20 formed on the for-

ward edge of base 8 and to which it is secured by bolts 19.

With this construction, it will be readily apparent that the forward end of the car is so constructed and reinforced as to properly support the boom structure (not shown) and withstand any blows imparted thereto by the manipulation of the dipper (not shown), at the same time providing the highly desirable beveled corners. To further insure against breakage by the dipper, the outer faces of castings 9 and 13 are formed with pockets 21 having suitable buffer blocks 22 readily detachably secured therein by bolts 23 passed through apertures in the blocks 80 and the walls of the pockets.

As best shown in Figures 2 and 3, casting 13 is provided with but a single row of buffer block receiving pockets, whereas castings 9 are provided with two rows of buffer block receiving pockets, as the dipper cannot strike the upper part of the casting 13. The buffer blocks may be of any desired material and, as they become broken or worn, can be renewed by removing securing bolts 23 and placing new blocks in the pockets.

From the foregoing description taken in connection with the accompanying drawing, it will be readily obvious that in this construction the advantages of the beveled corners are obtained and the necessary strength provided by the combination of the forwardly extending side castings, the web reinforcements in the inner I-beams and the transverse buffer casting bridging the inner I-beams under the main base plate front end.

What is claimed is:

1. An end construction for an excavator car, comprising a boom supporting base plate, inner sills extending to the outer end of the base plate, shorter outer sills, and a transom structure binding the inner and outer sills together, said transom structure including separator casting which form substantially bevel corners for the car.

2. A front end construction for an excavator car, comprising a boom supporting main base plate, a pair of inner sills extending forward to the end of the main base plate, a pair of shorter outer sills, and a transom structure binding the inner and outer sills together, said transom structure including a pair of separator castings which form bevel corners for the car.

3. An end construction for an excavator car, including supporting sills, a boom supporting base plate mounted on the sills, a transom structure binding the sills together, said transom structure including a separator casting having pockets formed therein, and buffer blocks secured in said pockets.

4. An end construction for an excavator car, including supporting sills, a boom supporting base plate mounted on the sills, a

transom structure binding the sills together, said transom structure including a separator casting having pockets formed therein, and renewable buffer blocks secured in said 5 pockets.

5. An end construction for an excavator car, including a boom supporting base plate, I-beams extending to the outer end of the base plate, and a bridge and buffer member 10 extending across the outer ends of the I-beams, said member having pockets formed therein for buffer blocks.

6. An end construction for an excavator car, including a boom supporting base plate, I-beams extending to the outer end of the base plate, a bridge and buffer casting extending across the outer ends of the I-beams, said casting having pockets formed 15 therein, buffer blocks secured in the pockets, and web reinforcements for the I-beams.

7. A front end construction for an excavator car, comprising a boom supporting main base plate, a pair of inner sills extending forward to the end of the base plate, a pair of shorter outer sills, a bridge and buffer casting connecting the forward ends 20 of the inner sills, and a transom structure binding the adjacent inner and outer sills together and including a pair of separator 25 castings which form bevel corners for the car.

8. A front end construction for an excavator car, comprising a boom supporting main base plate, a pair of inner sills extending forward to the end of the base plate, a pair of shorter outer sills, a bridge and buffer casting connecting the forward 30 ends of the inner sills, a transom structure binding the adjacent inner and outer sills together and including a pair of separator 35 castings which form bevel corners for the car, and buffer blocks carried by the bridge and buffer casting and the separator castings.

40 9. A front end construction for an excavator car, comprising a boom supporting

main base plate, a pair of inner I beam sills extending forward to the end of the base plate, a pair of shorter outer sills, a bridge and buffer casting binding the inner sills 50 together, a transom structure binding the adjacent inner and outer sills together and including a pair of separator castings which form bevel corners for the car, web reinforcing means for the inner sills, and 55 buffer blocks carried by the bridge and buffer casting and the separator castings.

10. An end construction for an excavator car, including a base plate, a transverse bridge member positioned with its upper 60 edge adjacent the outer end of the base plate, and an apron carried by the base plate and projected over the bridge member.

11. An end construction for an excavator car, including a base plate, a transverse bridge member positioned with its upper edge adjacent the outer end of the base plate, a depending apron carried by the outer 65 end of the base plate and projected 70 over the front face of the bridge member, and means securing the apron to the bridge member.

12. An end construction for an excavator car, including a base plate, brace means terminating adjacent the outer end of the base plate, a bridge casting extending across the outer ends of the brace beams with its upper edge adjacent the base plate outer end, an apron angularly projected from the base 75 plate and extended over the front face of the bridge casting, and securing means rigidly connecting the apron and bridge casting.

In testimony that we claim the foregoing 80 we have hereunto set our hands at South Milwaukee, in the county of Milwaukee and State of Wisconsin.
